Primary Examiner — Khawaja Anwar(74) *Attorney, Agent, or Firm* — Bradford B. Wright(57) **CLAIM**

The ornamental design for a coated abrasive belt, as shown and described.

DESCRIPTION

FIG. 1 is a perspective view of a coated abrasive belt showing an ornamental design in accordance with the present disclosure. As shown, the coated abrasive belt is oriented with the top surface shown uppermost on the coated abrasive belt;

FIG. 2 is an enlarged view of region 2 in FIG. 1;

FIG. 3 is a top view of the coated abrasive belt;

FIG. 4 is a back side view of the coated abrasive belt;

FIG. 5 is a front side view of the coated abrasive belt;

FIG. 6 is a left side view of the coated abrasive belt; and,

FIG. 7 is a right side view of the coated abrasive belt.

The broken lines shown in FIGS. 1-7 form no part of the claimed design.

1 Claim, 4 Drawing Sheets(56)
